AUTOMATIC PHONOGRAPH

John Gabel, Evanston, Ill., assignor to The John Gabel Manufacturing Company, Chicago, Ill., a corporation of Illinois

Application August 30, 1940, Serial No. 354,867

9 Claims. (CL. 274—10)

This invention relates to improvements in automatic phonographs and more particularly to automatic phonographs wherein there is a record magazine adapted to contain a plurality of records which may be played one by one in the order in which they are disposed in the record magazine, or wherein they may be played selectively as determined by the person operating the device.

The main objects of the invention are to provide an automatic phonograph which will be adapted to operate and to reproduce records one by one in the order in which they are disposed in the record magazine, without attention from an operator except for the matter of initiating operation of the machine by turning on power for operating the same, or by the deposition of coins for that purpose if the machine is coin controlled; to provide improved mechanism for permitting selective reproduction of the records; to provide selecting means which may be manipulated while the apparatus is in operation; to provide selecting mechanism whereby a plurality of records may be pre-selected in advance either while the machine is operating or while it is inoperative, or both; to provide mechanism which is relatively simple but durable and efficient; and in general, it is the object of the invention to provide an improved automatic phonograph of the character indicated.

Other objects and advantages of the invention will be understood by reference to the following specification and accompanying drawings (5 sheets) wherein there is disclosed an automatic phonograph apparatus embodying a selected form of the invention.

In the drawings:

Fig. 1 is a longitudinal vertical section;

Fig. 2 is a plan section on the line 2—2 of Fig. 1;

Fig. 3 is a vertical section of the mechanism on a vertical plane passing through the line 3—3 of Fig. 2;

Fig. 4 is a perspective illustrating a detail of construction which is also shown in Fig. 3;

Fig. 5 is a fragmentary side elevation of the improved selecting mechanism, portions thereof being broken away or omitted to more clearly illustrate other portions of the mechanism;

Fig. 6 is a plan section corresponding to a portion of Fig. 2 but showing the parts in a changed position; and

Fig. 7 is a perspective illustrating the principal elements of the apparatus.

The automatic phonograph apparatus herein

shown is generally of the type shown in Patents No. 2,086,095 and No. 2,161,483.

The apparatus herein shown is driven by an electric motor 10, the driven shaft 11 of which is extended upwardly and has secured to its upper end a turn table 12. When the apparatus is set in operation, the motor, its shaft 11 and the turn table 12 are continuously rotated including the time during which records are being transferred from the record magazine to the turn table and back again. The motor, shaft and turn table are suitably supported and journaled in frame work of the apparatus which is in its entirety designated 13.

15 A record magazine designated 14 in its entirety includes a series of vertically spaced, horizontally disposed shelves 15 which are carried by a suitable supporting frame structure 16, the latter being vertically slidably mounted on guide rods 17 which in turn are supported by the main frame 13.

15 The record magazine 14 has depending from it a rack bar 18 which meshes with a gear 19, the latter being rotatably mounted on a shaft 20. The shaft 20 is suitably journaled in bearings carried by the frame 13 and it has secured to it a ratchet wheel 21 which is adapted to be driven in one direction by a suitable pawl mechanism which will presently be described.

25 The weight of the magazine 14 is counterbalanced by means of a helical coil spring 22 which has one end adjustably anchored to a part of the main frame 13 as best shown in Figure 1, the other end of the spring being connected as indicated at 23 by means of a flexible wire or cord 24 to the periphery of a pulley 25. The said pulley 25 is secured in eccentric relation to another and larger pulley 26, the two pulleys being rotatably carried by a shaft 27 which is suitably journaled in portions of the frame structure 13. The large pulley 26 has a flexible wire or cord 28 connected to it as indicated at 29, the other end of such cord being connected as indicated at 30 to the lower end of the rack bar 18.

35 It will be seen that the contractile force of the spring 22 will be transmitted through the pulley 25 to the pulley 26 and through the cord 28 to the magazine rack bar 18 so as to tend to lift the rack bar and thereby elevate the magazine. The spring 22 is of such strength that it at no time is sufficient to elevate the magazine when loaded with records, but serves to merely counter-balance the same so that but little extra force is required to elevate the maga-

zine. The relationship existing between the weight of the magazine and the force of the spring is such that the magazine will descend incident to its own weight, stretching the spring incident thereto, unless such descent is prevented by other means.

The eccentric relation of the pulley 25 to the pulley 26 is such that when the spring 22 is stretched and thereby has its contractile force increased, it transmits its force through a short lever arm length portion of the eccentric pulley 25 to the pulley 26, and by the same token, when the contractile force of the spring is reduced, it transmits such force through a longer lever arm length of the pulley 25, so that there is a substantial equalizing of the counter-balancing effect of the spring 22 regardless of the extent to which it is stretched. This arrangement aids in the production of an easily and smoothly operating mechanism.

Downward movement of the magazine under its own weight is normally prevented by either or both of a pair of pawls 160 and 161 (see Figures 1 and 7) which serve this function in addition to a main purpose which will presently be described. The ratchet wheel 21 is in turn connected to the gear 19 through the agency of a dog 35 pivoted intermediate its ends as shown at 36 to the ratchet wheel 21.

The inner end of the dog is arranged to abut a pin 37 which extends from the face of the gear 19 which is adjacent the ratchet wheel 21 and the other end of the dog 35 is adapted to engage a stop pin 38 which serves to position the dog as shown in Figure 1. A spring 39 is provided for normally holding the dog in engagement with the stop pin 38 while permitting the dog to be displaced therefrom as will presently appear. It will be seen that any tendency of the magazine 14 to move downwardly is transmitted from its rack bar 18 to the gear 19 and from the gear 19 through its pin 37 and the dog 35 to the ratchet wheel 21, the latter being held against rotation by the pawls 160 and 161.

From the position of the mechanism shown in Figure 1, the mechanism is next operated to transfer a record from the magazine 14 to the turn table 12. This operation is effected by means of a cam 40 which is formed as a part of a wheel or disc 41 having thereon a plurality of cams and which wheel is carried by a shaft 42 suitably journaled for rotation in fixed posts or the like carried by the frame 13. The shaft 42 and its cams are rotatably driven from the motor driven shaft 11 through the agency of a worm gear 43 on the shaft 11 and a worm wheel 44 on the shaft 42. The worm gear 43 is freely rotatable on the shaft 11 and it is adapted to be clutched to the shaft through the agency of a clutch member 45 which is vertically slidably keyed to the shaft 11. Any suitable form of disengageable interconnection may be provided between the adjacent ends of the worm gear 43 and clutch sleeve 45. The means for controlling the clutch sleeve 45 will presently be described.

The cam 40 engages a roller 46 which is carried by a rod or strap 47, the latter being pivotally connected at one end as indicated at 48 to an arm 49 which at its lower end is pivotally mounted as indicated at 50 in a frame portion provided for that purpose. The other end of the rod 47 is pivotally connected as indicated at 51 to an arm 52 which has its lower

end pivotally mounted as indicated at 53 in conveniently accessible portions of the frame 13.

The upper end of the arm 52 is provided with a laterally extending finger 54 which is adapted, when the arm 52 is rocked to the left (in Figure 1) to engage the adjacent edge portion of a record in the magazine and move such laterally sufficiently to cause it to enter between a pair of feeding rolls 55 and 56 which are suitably journaled in the frame structure 13.

The upper roll 55 is preferably geared to the lower roll 56 so as to be rotated in unison therewith but in the opposite direction (as shown in Patent No. 2,161,433) and the lower roll 56 is positively driven so that said pair of rolls is capable of propelling the record from the magazine 14 to the turn table 12.

When the record feeding arm 52 is moved to the left as above mentioned, the arm 49 is also moved to the left so as to cause its laterally extending upper end portion 57 to be moved from its illustrated position overlying a portion of the turn table 12, thereby to clear the turn table for the reception of the record being delivered thereto by the feed rollers 55, 56. A suitable spring 58 stretched between a portion of the rod 47 and a transversely extending portion of a member 91 (see Fig. 2) serves to cause the roller 46 to operatively engage the cam 40.

The driven roller 56 is driven by means of a suitable connection, including a chain 59, to a disc 60 which is adapted to be rotated alternately in opposite directions by engagement with the under side of the turn table disc 12 and the top surface of a disc 61 which is secured to the motor driven shaft 11. The disc 60 is rotatably carried by an arm 62 which is pivotally mounted as indicated at 63 so as to permit the disc 60 to be moved vertically between the turn table 12 and disc 61.

The position of the disc 60 is controlled by the bar 47 which has an upstanding post part 63 provided with a pin 64 which is adapted to engage either of a pair of spring fingers 65 and 66 which depend from said arm 62. When the bar 47 is moved to the left by the cam 40, the pin 64 will engage the spring finger 66 and rock the arm 62 and its disc 60 upwardly and will serve to yieldingly hold the disc 60 in frictional driving engagement with the lower surface of the turn table 12.

When the disc 60 is driven by engagement with the turn table 12 it will be rotated in a counter-clockwise direction (as viewed in Figure 1) and will transmit similar rotation to the lower feeding roll 56, whereby the latter, in cooperation with the roller 55, is capable of feeding the record as above explained.

When delivery of the record to the turn table has been completed, a centering pin 67 is automatically lowered through the usual central hole in the record and into a suitable hole in the turn table 12. The centering pin 67 is carried by an arm 68 which is rigidly secured to the upper end of a vertically slidably mounted rod 69, the same being slidably supported by frame portions provided for that purpose.

The weight of the arm 68 and rod 69 normally tends to cause it to move downwardly and such movement is controlled by a cam 70 formed on said cam disc 41. The cam 70 engages a cam following roller or stud 71 carried by a rock arm 72 which is pivotally mounted intermediate its ends as indicated at 73 on a suitable ear or lug

ormed as a part of the frame 13, the other end of the rock arm 72 being adapted to engage a pin 74 which projects from the vertically slidably mounted rod 69. The cam 70 is so timed that when the record has been delivered to the turn table, the rock arm 62 will be permitted to rock counter-clockwise (in Figure 1), thereby permitting downward movement of the rod 69, arms 68 and centering pin 67. A suitable helical coil spring 75 extending between a portion of the rock arm 72 and the rod 69 is provided for normally maintaining the cam follower 71 of the rock arm in engagement with the cam 70. Said spring also asserts a downward force on the rod 69, the arm 68 and the centering pin 67.

When a record has been delivered to the turn table and locked in operative position thereon by the centering pin 67, rotation of the cam shaft 42 is stopped by effecting disengagement of the clutch sleeve 45 from the worm gear 43. The clutch sleeve 45 is controlled by a lever 76 which has a forked end 77 engaging in an annular recess in the clutch sleeve and the other end of said lever 76 is pivotally connected as indicated at 78 to the vertically movable rod 69.

The lever 76 is adapted to engage a shoulder 79 formed in an upwardly extending lever 80, the latter being pivotally mounted near its lower end as indicated at 81. A spring 82 connected between the lower end of the lever 80 and a conveniently located portion of the frame structure 13 serves to normally rock the lever 80 in such a direction that the shoulder 79 thereof will overlie the lever 76.

The rocking movement of the member 80 under the influence of the spring 82 is limited by engagement of the upper end portion of the member 80 with a pin 83 carried by a member 84 which is pivotally mounted on a frame part 13 and held against rotation in one direction by means of a stop pin 85. By this means frictional contact between the vertical edge of the member 80 and adjacent vertical face of the lever 76 is avoided so as to insure freedom of movement of the lever 76 relative to the member 80. When the rod 69 is moved downwardly, the lever 76 is also moved downwardly and comes into engagement with the shoulder 79 which thereupon acts as a fulcrum so as to cause the clutch sleeve engaging end of the lever 76 to rock upwardly. Such upward rocking movement of the clutch engaging end of the lever 76 serves to disengage said clutch member 45 from the worm gear 43, whereupon rotation of the cam shaft 42 ceases.

Incident to the lowering of the centering pin 67, a pick-up member 86 is lowered into operative engagement with the record then on the turn table. The pick-up member 86 is carried by an arm which is mounted so as to be both vertically and horizontally movable. The pick-up member 86 also has connected with it mechanism such as illustrated herein and which is fully illustrated and described in the aforesaid Patents No. 2,087,095 and No. 2,161,483 for rocking the member 80 against the force of the spring 82 upon completion of the reproduction of a record.

By such means, which is not a part of the present invention and hence not described in detail, the arm 80 is rocked sufficiently to remove the shoulder 79 from under the lever 76, thereby permitting the clutch sleeve engaging end of the lever and the clutch sleeve to move downwardly by gravity to re-engage the worm gear 43 and again set in motion the cam shaft 42. Thereupon, the cam 40 permits the spring

58 to move the rod 47 to the right (in Figure 1) with the result that the record shifting arm 49 engages the edge of the record on the turn table and moves it laterally into engagement with the feeding rolls 55 and 56 which are then operative to feed the record back into the place in the magazine from which the record was originally discharged.

By examination of Figure 1 of the drawings 10 it will be seen that incident to movement of the member 47 toward the right, the pin 64 will engage the spring finger 65 and move the wheel 60 downwardly into driving engagement with the disc 61 to thereby rotate the feeding rollers 55 15 and 56 in the proper direction for transferring the record from the turn table to the magazine. It may be observed that during the playing of a record, the member 47 is held in an intermediate position by the cam 40 so that the disc 60 is held out of contact with both the turn table 12 and disc 61, whereby the feeding rolls 55 and 56 remain stationary during reproduction of a record.

As soon as the record is restored to the magazine a cam 87 engages a roller 88 carried by an 20 arm 89 to rock said arm in a clockwise direction (Figure 1) about the pivotal mounting 90 of said arm. The arm 89 has a link 91 pivotally connected to it as indicated at 92, the other end of said link 91 being pivotally connected as indicated at 93 to an arm 94 which is pivotally mounted at its lower end as shown at 95 on a frame portion 13. The arm 94 is extended upwardly above the link 91 and is provided with a dog 96 which is adapted to engage with the teeth 35 of a rack or comb-like member 97 which is carried by the depending post of the record magazine.

As shown in Figure 1, the dog 96 is out of engagement with the member 97, so that the 40 magazine is unlocked or free to move vertically. During the time that a record is being transferred between the magazine and turn table and during the time that a record is being reproduced, the dog 96 is in locking engagement with said member 97 so as to prevent movement of the magazine and to thereby retain the magazine in position for receiving the record in its original location upon completion of the reproduction thereof. The cam 87 is so formed that during the reproduction of a record and during the shifting of a record, said dog 96 is permitted to engage the member 97.

The link 91 is extended beyond the arm 94 and has a pawl member 98 pivoted to its outer end as 55 indicated at 99. The other end of the pawl 98 is provided with an ear or dog 100 which is adapted to engage the teeth of the ratchet member 21, a suitable spring 101 being provided between the pawl 98 and the upper end portion of the member 94 for yieldingly holding the pawl in operative engagement with said ratchet wheel. When the link 91 moves to the right, the pawl 98 is correspondingly moved to the right and thereby rotates the ratchet wheel 21 to a predetermined extent (as determined by the travel of the link 91). The rotation of the ratchet wheel 21 is transmitted through the previously described dog 35 and pin 37 to the gear 19 which in turn transmits upward movement to the rack bar 18 and the magazine 14.

Assuming that the records are to be played in the order in which they are positioned in the magazine, the magazine will come to rest as soon as it has been raised a distance corresponding to 70 the vertical spacing of the records in the maga-

zine. Thereupon, the record transferring mechanism will again be operated by the cam mechanism already described and the next record will be transferred to the magazine, reproduced and then returned to the magazine, followed by successive repetitions of the operations thus far described.

When the lowermost record in the magazine has been reproduced and returned to the magazine, the dog 35 carried by the ratchet wheel 21 will reach a position wherein its outer end will come into engagement with a lug 102 formed as a part of the frame 13 and will be thereby rocked on its pivot 36 so as to clear the pin 37 of the gear 19, thereby permitting the gear 19 to rotate on the shaft 20 independently of the ratchet wheel 21. The weight of the loaded magazine 14 will then cause the magazine to move downwardly by gravity, the rack bar 18 in turn causing the gear wheel 19 to rotate in a rearward or clockwise direction (Figure 1). Downward movement of the magazine is limited by engagement of the lower ends 103 (Figure 3) of the magazine structure with cushioning springs 104 carried by the guide rods 17.

So far as concerns the reproduction of the records successively in the order in which they are positioned in the magazine, the apparatus is then ready to effect transfer of the top record in the magazine to the turn table. However, because of selecting mechanism presently to be described, the arrangement is such that the ratchet wheel 21 is fed a number of steps before its dog 35 is re-engaged with the pin 37. It will be understood that incident to full downward movement of the magazine, the gear 19 is rotated somewhat less than one complete revolution, so that its pin 37 does not return to the position it occupied when the magazine was in its highest position. Hence, a certain amount of rotation of the ratchet wheel 21 independently of the gear 19 is permitted.

The apparatus herein disclosed comprises mechanism whereby a selection may be made of certain of the records in the magazine. The arrangement is such that any number of the records may be selected, omitting all others. If the magazine holds twenty-four records, there are provided twenty-four keys respectively corresponding to each record holding pocket of the magazine. Any of the keys may be depressed to select the corresponding records which will then be played in the order in which they appear in the magazine.

For example, if the records are indicated by numerals 1 to 24, inclusive, and it is desired to reproduce records numbered 3, 9 and 18, these records will be reproduced successively in the order of their numbers if the selection is made when the magazine is disposed in a position with either of records numbered 1, 2 or 3 in alignment with the turn table. However, if at the time of selection, the magazine is in such position that record numbered 7 is on the turn table or in the magazine in alignment with the turn table, the selected records would be played in the order 9, 18, 3. This follows from the above described arrangement whereby the magazine is moved continuously in one direction for successively reproducing the records and then returned automatically to its initial or starting position.

The selecting mechanism herein disclosed comprises a bank of keys, each key being designated K, and each key being independent of the other. Each key is carried by a bell crank arm 105 which

is pivoted on a shaft or rod 106 which is carried by a bracket-like member 107. The bracket member 107 is in turn secured to suitable lugs or ears 108 formed as a part of or attached to the frame structure 13.

Each bell crank 105 includes a depending arm 109 which is movable in a slot such as 110 formed in a laterally extending flange 111 on the lower end of the bracket plate 107. The depending arm 109 is thereby firmly supported against lateral displacement from its proper operative position. The horizontally extending or top arm 112 of each bell crank has an extension 113 beyond the pivot 106, said extension being provided with a rounded end portion 114 adapted to cooperate with a helical spring 115 which is carried by a channel shaped bracket 116.

The channel shaped bracket 116 is suitably mounted on parts of the frame 13 or brackets 20 carried thereby, and the spring 115 is held in spaced relation to the bottom of the channel by means such as ears 117 pressed forwardly from said bottom. The ends of the spring are anchored to the supporting channel in any suitable manner such as indicated at 118 in Figure 5.

The rounded end portions 114 of the bell cranks 105 normally extend beyond the front or adjacent surface of the coil spring 115. As indicated in Figure 3, the spring overlies the end portion 114 and thereby serves to yieldably retain the bell crank member 105 in the position illustrated in full lines. By pressing downwardly on the key, the bell crank arm 105 may be rocked to the position illustrated in dotted lines in Figure 3, the spring 115 yielding and permitting the said rounded end portion 114 to move upwardly past the spring, whereupon the spring restores itself to a position underlying said end portion as is also indicated in Figure 3. The spring is then effective to retain the key in its depressed position until some other force restores it. It will be apparent that only a light force is required to adjust the key either up or down, the force required being somewhat dependent upon the strength of the helical spring 115.

To more adequately support the spring 115 against vertical displacement incident to the movement of the key, the channel 116 extends well over the top and bottom of the coil spring but it is notched out as indicated at 119 to permit said rounded end 114 to pass through the channel as will be apparent from an inspection of Figure 3. A stop bar 120, carried by the frame or bracket part on which the bracket plate 107 is mounted, serves to limit the upward swinging movement of the key and thereby to position all of the keys in horizontal alignment. Downward movement of the keys is limited by engagement of a shouldered portion 121 of each key with the face of the bracket plate 107 as is indicated in Figure 3.

Each bell crank arm 109 extends downwardly below the laterally extending flange 111 and is provided with a laterally extending lip or ear 65 122 for a purpose which will presently appear.

The depending arms 109 of the bell cranks 105 are each adapted to actuate a bar 123 which is carried by a pair of parallel links 124, the latter being pivotally connected at their outer ends to said bar 123 and pivotally mounted at their inner ends as indicated at 125 on portions of the frame 13 or suitable brackets secured thereto. One end of an arm 126 is pivotally connected to the bar 123, the arm extending inwardly in engagement

with an upstanding part of the frame structure 13 (see Figs. 2 and 7).

A spring 127 connected between the arm 126 and the frame part 13 serves to normally maintain said arm against the frame part and to maintain the arm and bar 123 in outwardly disposed position as illustrated in Figures 2 and 3. The inner end of the arm 126 is bevelled as indicated at 129 and provided with a notch or recess 130 for cooperating with a pin 131 which extends upwardly from a member 132.

The member 132 is of generally H-shape, having depending legs 133 which are pivotally connected at their lower ends to suitable ears or lugs formed integrally with the frame structure 13 (see Figure 3). One upwardly extending arm 134 of said H-shaped member is connected by means of an adjustable link 135 to a cam member 136 which is pivotally mounted at its lower end as indicated at 137 on a frame part provided for that purpose. The cam member 136 is provided at its upper end with a cam formation 138 which engages an ear 139 provided on the clutch controlling lever 76. A spring 140 stretched between a conveniently located frame part and said cam plate member 136 serves to normally urge the cam plate to rock in a clockwise direction (Figure 7) to thereby move the clutch sleeve 45 upwardly into driving engagement with the hub of a disc 141 which is suitably rotatably mounted on the shaft 11 and maintained in predetermined vertical position on said shaft.

It will be seen that the spring 140 transmits its force through the cam plate 136 and the link 135 to the H-shaped member 132, so that the latter with its upstanding pin 131 is normally urged to rock in a clockwise direction as viewed in Figures 1 and 7.

Clockwise rocking movement of the member 132 is prevented during the time that a record is being reproduced by engagement of a pin 142 which projects from a part of the H-shaped member 132, with a pin 143 which projects from the bar 91. The bar 91 is the one which actuates the magazine lifting pawl 98 and it will be apparent that the spring 140 is not of sufficient strength to overcome the weight of the record magazine and records therein, as would be necessary to effect rocking movement of the member 132.

In the position of the apparatus shown in the drawings, the rod 91 is moved to substantially its extreme right-hand position in which the record engaging arms 49 and 52 are rocked to their respective extreme right-hand positions. Hence, in these views the pins 142 and 143 appear in spaced relation. However, it will be understood that when the mechanism is in record reproducing position the bar 91 is adjusted to the left so that its pin 143 does engage the pin 142.

When a key is depressed, the bar 123 is moved inwardly, swinging on its supporting links 124, thereby moving the arm 126 inwardly so as to cause its notch or recess 130 to be aligned with the pin 131. The inward movement of the member 126 is such that the bevelled end 129 thereof slides past the pin 131 without moving the pin or even without necessarily engaging it, although said bevelled edge is located in very close proximity to the side of the pin.

When the arm 126 is moved inwardly in the manner explained, the operation of the mechanism upon completion of the reproduction of a record is as follows. The cam shaft 42 and its cams are first caused to rotate incident to en-

gagement of the clutch sleeve 45 with the worm gear 43 as already explained. The cam 40 permits the spring 58 to effect transfer of the record from the turn table to the magazine and the cam 81 operates as usual to effect one step of upward movement of the magazine through the agency of the bar 91 and pawl member 98.

During the time the member 91 is moved to the right by the cam 81, movement of the H-shaped member 132 under the influence of the spring 140 is prevented by means of a link 144 which is pivoted at one end as indicated at 145 to a part of the member 132, the other end of the link being provided with an opening 146 having a shoulder 147 formed therein for engagement with a pin 148 which projects from a suitably located frame part. The pin 148 may be provided with a head as indicated in Figure 1 for maintaining the adjacent end of the link in operative relation to the pin. Normally, the shoulder 147 engages said pin 148 which is fixed and thereby constitutes a stop serving to prevent movement of the link 144 to the right as is required incident to the rocking movement of the member 132 under the influence of the spring 140.

Upon completion of the said step of upward movement of the record magazine, the link 144 is moved upwardly so as to disengage the shoulder 147 from the pin 148, thereby to permit the link 144 and the H-shaped member 132 to be rocked by the spring 140. To effect such disengagement of the shoulder 147 from the pin 148, the link is provided with a laterally extending arm part 149 which is adapted to be engaged by a crank pin 150, carried by the cam disc 87 in such a location that it will engage and lift said arm part and link 144 upon completion of said step of upward movement of the record magazine.

The key controlled member 126 having already been moved inwardly, the recess 130 therein is adapted to receive the pin 131, thereby permitting said rocking movement of the member 132 by the spring 140.

When the member 132 is permitted to rock in the manner explained, the cam plate member 136 is also rocked in a clockwise direction, whereby its cam edge 138 operates against the finger or lip 139 of the clutch sleeve controlling arm 76 to raise the clutch sleeve 45 into driving engagement with the disc 141. The driving engagement between the clutch sleeve 45 and worm gear 43 is thereby incidentally disengaged, with the result that the cam shaft 42 and cams come to rest.

The disc 141 carries a crank pin 151 which is adapted to operate against the arms 152 and 153 of a lever 154 which is pivotally connected to the frame structure as indicated at 155. The rotation of the disc 141 and its crank pin 151 will thus serve to rock the arm 154 back and forth once for each revolution of the disc 141. The arm 154 is connected by means of a link 156 to one arm 157 of a bell crank, the other arm of which is indicated at 158. The bell crank comprising the arms 157 and 158 is pivotally mounted as shown at 159 on an adjacent frame part.

The arm 157 has pivotally connected to it a dog 160 which engages the ratchet wheel 21 in such a manner that when the bell crank is rocked in a counter-clockwise direction the ratchet wheel is correspondingly advanced in a counter-clockwise direction. The arm 158 has secured to it a pawl 161 which engages the teeth of the ratchet 21 in such a manner that when the bell crank is rocked in a clockwise direction, the ratchet wheel

is again advanced in a counter-clockwise direction.

It will thus be seen that the disc 141 and its crank pin 151 in cooperation with the arm 154, link 158 and the described bell crank arms 178, 158 operate to effect two steps of movement of the ratchet wheel 21 for each revolution of the disc 141. In this manner a quick acting magazine elevating movement is obtained. Suitable springs indicated at 162 are provided for normally urging the pawls 160 and 161 into operative engagement with the ratchet wheel 21.

The quick acting magazine elevating movement continues until such time as the H-shaped member 132 is restored to its normal position whereby the cam plate 136 with its clutch controlling cam 138 is also restored to initial position to effect disengagement of the clutch member 45 and disc 141.

The shaft 20 which rotates with the ratchet wheel 21 carries a sprocket member 163, the said sprocket being secured to the shaft so as to rotate in unison therewith and in unison with the ratchet wheel 21. The sprocket 163 meshes with an endless chain 164 which is supported by suitable sprocket wheels 165 and 166, which are rotatably mounted on the frame structure 13. The chain 164 carries a pair of brackets 167, one for each reach of the chain, such brackets being so formed as to constitute one of the links of the chain so as to be movable therewith as a part of the chain. As shown in Figure 4, each bracket 167 is in the form of an inverted U-shaped member. A lever 168 is pivotally mounted intermediate its ends as indicated at 169 on the top of each of said brackets 167, a suitable spring means such as indicated at 170 being provided for yieldably maintaining the lever in predetermined position substantially as illustrated in Figure 4.

Only the upper reach of the chain 164 is operatively related to the mechanism wherefore a pair of said bracket devices 167 are employed so as to make both halves of the chain successively operable. The bracket 167 on the upper reach of the chain carries its arm 168 horizontally with its inwardly extending end portion 171 in abutting sliding relation to a bar 172. The bar 172 is pivotally suspended by means of upstanding end arms 173 which are pivotally connected as shown at 174 in Figure 5 to suitable lugs or similar portions of the frame 13. A spring 175 is provided for yieldably maintaining the member 173 in outwardly disposed position as determined by a suitable pin 176 with which one of the arms 173 engages.

When the outwardly extending end portion 171 of the lever 168 comes into engagement with the arm 169 of a depressed key, the lever 168 will be rocked in a clockwise direction (Figure 2) incident to the advancing movement of the chain 164, and the inner end portion 171 of said arm 168 will be swung inwardly (Figure 6) thereby incidentally moving the bar 172 inwardly.

The bar 172 is adapted to engage the arm 178 of a bell crank member, the other arm of which is indicated at 179, and which bell crank is pivotally mounted as indicated at 180 on a suitable frame part. In the position of the mechanism shown in Figure 2, the arm 178 is spaced from said member 172 but when the H-shaped member 132 is rocked in a clockwise direction as already described, the bell crank arms 178 and 179 will also be rocked in a clockwise direction (in Figure 2) so as to cause the end portion of the arm 178 to engage the adjacent face of said bar

172. Such rocking movement of the bell crank arms 178 and 179 is effected by means of an upward extension of the pin 131 which projects through a slot 181 in the end portion of the bell crank arm 179.

When the bar 172 is rocked inwardly in the manner explained, its movement is transmitted to the bell crank arms 178 and 179 which are then rocked in a counter-clockwise direction (in Figures 2 and 7) with the result that the movement of the arm 179 is transmitted through the pin 131 to the H-shaped member 132, so as to restore the same to its initial position. The cam plate 136 is thereby restored to its initial position, thereby effecting disengagement of the clutch sleeve 45 and the disc 141, and re-engagement of the clutch sleeve 45 with the worm gear 43.

Upward movement of the magazine is then terminated and the cam shaft 42 with its cams again caused to rotate. The cam 87 thereupon permits the member 91 to be returned by the spring 58 to its normal position, thereby causing the dog 96 to lock the magazine in its adjusted position. The cam 40 also actuates the bar or link 41 to effect transfer of a record from the magazine to the turn table and the other operations of reproducing the selected record follow according to the manner already explained.

For restoring the depressed key so as to get it out of the way of the end portion 171 of the arm 168, each bracket member 167 carries a pin 182 slidably mounted in the opposite sides of the bracket and yieldingly held in inwardly disposed position as illustrated in Figures 3 and 4 by a coil spring 183 which is interposed between one of the side arms of the bracket 167 and a suitable collar carried by the pin 182.

The inner end of the pin 182 is disposed adjacent a bar 184 which is pivotally mounted through the agency of depending end arms 185 on suitably located frame portions as indicated at 186. A spring such as indicated at 187 is provided for yieldingly holding the bar 184 in inwardly disposed position as illustrated in Figure 3 wherein it is supported by engagement with a suitable abutment 188 which, in this instance, comprises part of the frame structure on which the bell crank arms 178 and 179 are pivoted.

A bell crank comprising arms 189 and 190, pivotally mounted as indicated at 191 on a part of the frame structure is associated with the bar 184, the arm 190 being located in the horizontal plane of said bar so as to be adapted to engage and rock the bar outwardly. The inner end of the bell crank arm 189 is provided with a slot 192 which receives the upper end portion of a pin 193, which extends upwardly from an arm 194 which is pivotally mounted at its lower end as indicated at 195 on a suitably provided lug or ear of the frame 13. The arm 194 carries a roller 196 which is adapted to be engaged by a cam element 197 for rocking the arm 194 counter-clockwise as seen in Figures 1 and 7.

The rocking movement of the arm 194 thus effected is transmitted into rocking movement of the bell crank arms 189 and 190, whereby the arm 190 engages or forces the bar 184 to move outwardly. Incident to the outward movement of the bar 184, it engages the adjacent end of the pin 182, moving said pin outwardly so that the outer end of the pin 182 will engage the ear or flange 122 of the bell crank arm 189 to thereby return the same from its dotted line position as

shown in Figure 3 to its full line position as there shown.

The cam 197 is relatively short as seen in Figure 1 and it releases the arm 194 as soon as restoration of the selector key has been completed, whereupon the spring 187 operates to return the bar 184, the bell crank arms 189 and 190 and the arm 194 to normal, inactive position.

In the chain carried operating mechanism described, the relationship of the two actuating brackets 167, 167 is such that when the bracket on the uppermost reach of the chain 164 is in operative relation to the key K-24 at one end of the bank of keys (which key represents the record at the bottom of the magazine), the other actuating bracket 167 is located immediately below the sprocket 165 at the other end of the bank of keys. With each step of vertical movement imparted to the magazine, the chain 164 is moved a distance which is equal to the distance between adjacent key arms 109; hence, it will be necessary to effect extra travel of the chain 164 when the magazine is shifted from its uppermost position to its lowermost position, in order to move the bracket 167 from below the sprocket 165 to position on the uppermost reach of the chain adjacent the arm 109 of the first key indicated K-1. Such position of the bracket 167 relative to the first key arm 109 is required when the first record is to be reproduced in order that for subsequent records the member 161 will be properly related to the key arms 109 which represent the respective records.

The extra movement of the chain 167 is effected by means of a cam member 198 carried by the sprocket wheel 163 (Figures 3, 5 and 7). Said cam member 198 is adapted to engage a finger 199 which is rigidly secured to and depends from the bar 123. When the cam 198 engages said finger 199, the bar 123 is moved inwardly so that it adjusts the arm 126 into position wherein its recess 130 will permit the pin 131 to move into such recess, thereby permitting the H-shaped member 132 to move as required to effect rotation of the ratchet wheel 21 by means of the driven disc 141 and its crank pin 151 in the manner already explained.

For stopping the feeding operation of the disc 141 and its crank pin 151, the sprocket 163 is provided with a crank pin 200 which is adapted to engage the end portion 201 of an arm 202 which is pivotally mounted as shown at 203 on a portion of the frame 13. Said arm 202 has an edge portion or prominence 204 which is adapted to engage an adjustable abutment 205 carried by an extension arm 206 of the H-shaped member 132. Said crank pin 200 is so positioned on the sprocket wheel 163 that it will actuate the arm 202 and member 132 at the proper time to disengage the clutch sleeve 45 from the disc 141 to stop rotation of the latter when the bracket member 167 reaches its starting position on the upper reach of the chain.

The sprocket 163 is also provided with a peripheral recess 207, the same being adapted to permit passage of the depending portion of the bracket 167 and its arm 168 on the lower reach of the chain. This arrangement permits passage of the member 167 without impairing driving engagement between the sprocket 163 and the chain 164. During the rotation of the ratchet 21 as effected by the driving disc 141 during the operation of the cam 198, the pawl or dog 35 carried by the ratchet is not in engagement with the driving pin 37 of the gear wheel 19 but instead, is free thereof

and is moving toward said pin to re-establish its driving relation thereto. It will be remembered that incident to the lowering of the magazine, the gear wheel 19 was rotated in a reverse direction, the pin 37 being freed from the dog 35 and being carried by the gear 19 through a path of travel somewhat less than 360 degrees. In this way, the pin 37 temporarily acquires a position in advance of the dog 35 and the dog is, in effect, caught up with the pin 37 as an incident to the rotation of the ratchet 21 incident to the operation of the cam 198.

For the purpose of permitting accurate adjustment of the sprocket wheel 163 and chain 164 with the parts carried thereby relative to the magazine and its actuating mechanism, the sprocket 163 is preferably connected to the shaft 20 through the agency of an arm 208 which is fixedly secured to said shaft and is provided with a pair of ears 208' which embrace one of the spokes of the sprocket. Adjusting screws 209 carried by said ears 208' and adapted to engage the opposite edges of such spoke facilitate adjustment of the relative position of the sprocket and arm 208.

The described mechanism may have associated with it coin control mechanism such as indicated generally at 210 in Figure 2, the same being connected to the operating mechanism through a lever 211 pivoted on a part of the frame 13 and provided with an end portion 212 which is adapted to be engaged by a pin 213 carried by the cam disc structure as shown in Figures 2 and 7.

It will be observed that the structure as described is operative, in the absence of coin controlled mechanism, to continuously reproduce the records in the magazine successively, beginning with any of records in the magazine, then playing each of the records disposed in lower pockets until the lowermost record is reproduced, whereupon the magazine is lowered so that the top record will be reproduced followed by those disposed thereunder.

Similarly, in the pre-selection of records by means of the selector keys, the uppermost selected record (either in alignment with the turn table or in a position therebelow) will first be reproduced and then the selected records below such uppermost record will be reproduced successively in the order in which they appear in the magazine. Thereafter, any records which were selected from the magazine in positions above the record in playing position will be reproduced successively in the order in which they appear in the magazine.

The details of the described construction may, of course, be varied considerably without departing from the principles of the mechanism described, wherefore it should be understood that the following claims are not intended to be restricted to the specific details of construction but are directed to the structure required for carrying out the principles of operation embodied in the described structure.

I claim:

1. In an automatic phonograph, the combination of record playing mechanism, a magazine for storing a plurality of records, mechanism for transferring the records from the magazine to said playing mechanism and back again, said magazine being mounted for movement relative to said transferring mechanism whereby any selected record may be brought into position for transfer as aforesaid, clutch-controlled means for effecting movement of said magazine, and

selecting mechanism for permitting simultaneous selection of a plurality of the records in the magazine for reproduction, said selecting means comprising a plurality of aligned keys respectively related to the records in the magazine and adapted to be actuated for record selection purposes, an endless conveyor operatively connected to said magazine so as to move in synchronism therewith, said conveyor being elongated and having one reach arranged to travel along a path which is substantially parallel to said aligned keys, an abutment member carried by said means for successively engaging selected ones of said keys, and a single set of mechanical connections between said abutment member and said clutch for effecting disengagement thereof as an incident to engagement of said abutment means with any of said keys.

2. In an automatic phonograph, the combination of record playing mechanism, a magazine for transferring the records from the magazine to said playing mechanism and back again, said magazine being mounted for movement relative to said transferring mechanism whereby any selected record may be brought into position for transfer as aforesaid, means for effecting movement of said magazine, and selecting mechanism for permitting simultaneous selection of a plurality of the records in the magazine for reproduction, said selecting means comprising a plurality of aligned keys respectively related to the records in the magazine and adapted to be actuated for record selection purposes, an elongated endless conveyor operatively connected to said magazine so as to move in synchronism therewith, said conveyor being elongated and having one reach arranged to travel along a path which is substantially parallel to said aligned keys, an abutment member carried by said endless conveyor for successively engaging selected ones of said keys, and means actuated as an incident to engagement of said abutment means with a key, for stopping movement of said magazine.

3. In an automatic phonograph, the combination of record playing mechanism, a magazine for storing a plurality of records, mechanism for transferring the records from the magazine to said playing mechanism and back again, said magazine being mounted for movement relative to said transferring mechanism whereby any selected record may be brought into position for transfer as aforesaid, means for effecting movement of said magazine, selecting mechanism for permitting simultaneous selection of a plurality of the records in the magazine for reproduction, said selecting means comprising a plurality of aligned keys respectively related to the records in the magazine and adapted to be actuated for record selection purposes, an endless conveyor operatively connected to said magazine so as to travel in synchronism therewith, said conveyor being elongated and having one reach arranged to travel along a path which is substantially parallel to said aligned keys, an abutment member carried by said conveyor for successively engaging selected ones of said keys, said abutment member being movably mounted on said conveyor and caused to move relatively thereto by engagement with one of said keys, and a single set of mechanical devices actuated by said abutment member upon movement thereof for stopping movement of said magazine.

4. In an automatic phonograph, the combination of record playing mechanism, a magazine for storing a plurality of records, mechanism for

transferring the records from the magazine to said playing mechanism and back again, said magazine being mounted for movement relative to said transferring mechanism whereby any selected record may be brought into position for transfer as aforesaid, means for effecting movement of said magazine, selecting mechanism for permitting simultaneous selection of a plurality of the records in the magazine for reproduction, said selecting means comprising a plurality of aligned keys respectively related to the records in the magazine and adapted to be actuated for record selection purposes, an endless chain mounted for movement through a path of travel having an operative reach and a return reach and operatively connected to said magazine so as to be movable in synchronism with the movement of said magazine, a plurality of actuating devices movably mounted on said chain in such relation to each other that one of said devices is at all times associated with the operative reach of the chain, said actuating devices being adapted to successfully engage selected ones of said keys and to be thereby moved relative to said chain, and means actuated by said actuating devices for stopping movement of said magazine.

5. In an automatic phonograph, the combination of record playing mechanism, a magazine for storing a plurality of records, mechanism for transferring the records from the magazine to said playing mechanism and back again, said magazine being mounted for movement relative to said transferring mechanism whereby any selected record may be brought into position for transfer as aforesaid, means for effecting movement of said magazine, a plurality of keys respectively related to said records for permitting simultaneous selection of a plurality of the records in the magazine for reproduction, an endless member movable through a path of travel having operative and return reaches of which the operative reach is disposed adjacent portions of said selecting keys, means interconnecting said magazine and said endless member for coordinated movement, a plurality of actuating devices carried by said endless member in such relation to each other that one of said actuating devices is at all times disposed on the operative reach of said endless member and operatively associated with said keys, means controlled by each of said keys for initiating movement of said magazine, and mechanical means controlled by said actuating device for stopping the movement of said magazine upon engagement of said actuating device with a key.

6. In an automatic phonograph the combination of record playing mechanism, a vertically movable magazine for storing a plurality of records in vertically spaced relationship, mechanism for transferring the records from the magazine to said playing mechanism and back again, means for effecting step by step upward movement of said magazine to successively position the records therein for transmission as aforesaid by said mechanism, said means comprising a ratchet wheel, a gear connected to said magazine so as to be operative to move the latter upwardly as an incident to rotation of the gear, a pawl interconnecting said ratchet wheel and gear, means for advancing said ratchet and gear step by step, means operative as an incident to normal movement of said ratchet, gear and interconnecting pawl for effecting disengagement of the latter at predetermined times to permit downward movement of said magazine during a normal

step of movement of said ratchet, means for selecting for reproduction, any one of the records in said magazine, said means comprising an endless chain movable through an elongated path of travel and having operative and return reaches, means connecting said chain to said ratchet for step by step movement with the ratchet, a plurality of actuating devices carried by said chain in relatively spaced relation such that one of said devices is carried to the operative reach of the chain from the inoperative reach thereof during the downward movement of said magazine, and means adapted to be actuated by one of said devices when on the operative reach of said chain, for initiating movement of said magazine in excess of a normal step of movement thereof and for preventing operation of said record transferring mechanism during such excess movement of the magazine.

7. In an automatic phonograph, the combination of record playing mechanism, a magazine for storing a plurality of records, mechanism for transferring the records from the magazine to said playing mechanism and back again, said magazine being mounted for movement relative to said transferring mechanism whereby any selected record may be brought into position for transfer as aforesaid, means for effecting movement of said magazine, selecting mechanism for permitting simultaneous selection of a plurality of the records in the magazine for reproduction, said selecting means comprising an endless chain, relatively spaced, rotatably mounted sprockets for supporting said chain, means for driving said chain in a predetermined direction in synchronized relation to the movement of said magazine, a plurality of keys respectively related to the records in said magazine and adapted to be manually adjusted to record selecting position, said keys having arm portions disposed adjacent one reach of said chain, a movably mounted bar disposed in substantially parallel relation to said reach of the chain, means carried by said chain for moving said bar and adapted to be actuated by engagement with any one of said key arm portions as an incident to the movement of said chain, and means controlled by said bar for stopping operation of said magazine moving means.

8. In an automatic phonograph, the combination of record playing mechanism, a magazine for storing a plurality of records, mechanism for transferring the records from the magazine to said playing mechanism and back again, said magazine being mounted for movement relative to said transferring mechanism whereby any selected record may be brought into position for transfer as aforesaid, means for effecting movement of said magazine, selecting mechanism for permitting simultaneous selection of a plurality of the records in the magazine for reproduction, said selecting means comprising an endless chain, relatively spaced, rotatably mounted sprockets for supporting said chain, means for driving said chain in a predetermined direction in synchronized relation to the movement of said magazine, a plurality of keys respectively related to

the records in said magazine and adapted to be manually adjusted to record selecting position, said keys having arm portions disposed adjacent one reach of said chain, a movably mounted bar disposed in substantially parallel relation to said reach of the chain, means carried by said chain for moving said bar and adapted to be actuated by engagement with any one of said key arm portions as an incident to the movement of said chain, means controlled by said bar for stopping operation of said magazine moving means, means for restoring the engaged key to normal position comprising a bar disposed in substantially parallel relation to said reach of the chain and movable transversely relative thereto, means carried by said chain and in such position thereon as to be movable by said bar into engagement with a portion of said key and in such direction as to effect return of the key to normal position, and means for effecting operative movement of said bar.

9. In an automatic phonograph, the combination of record playing mechanism, a vertically movable magazine for storing a plurality of records in vertically spaced relationship, mechanism for transferring the records from the magazine to said playing mechanism and back again, primary driving means for effecting upward movement of said magazine step by step to bring the records successively into position for transfer as aforesaid, mechanism for permitting selection of any one of the records in the magazine for reproduction, said selecting mechanism comprising supplemental driving means for effecting extended step by step upward movement of the magazine, a series of keys respectively related to the records in said magazine, means actuated by said keys for initiating operation of said supplemental driving means, an endless chain movably supported so as to have operative and inoperative reaches, means for driving said chain comprising a driving sprocket engaging a portion of said chain, disengageable means interconnecting said driving sprocket and said magazine for effecting coordinated movement of said magazine and chain, a plurality of members carried by said chain in such spaced relation to each other that one of said members is carried to the operative reach of the chain as another member leaves the same, said members when on the operative reach of the chain being adapted to engage any selected key, means actuated as an incident to such engagement for stopping the operation of said supplemental driving means, means for effecting disengagement of said interconnecting means when said magazine reaches its uppermost position so as to permit downward movement thereof independently of said driving sprocket and chain, means carried by said sprocket for starting and stopping said supplemental driving means during the downward movement of the magazine to thereby advance the chain independently of said primary driving means so as to carry one of said members on the chain from the inoperative reach to the operative reach thereof.

JOHN GABEL.
